UNITED STATES PATENT OFFICE.

ARCHIBALD G. SHAVER, OF CHICAGO, ILLINOIS, ASSIGNOR TO REGAN SAFETY DEVICES COMPANY, INC., A CORPORATION OF NEW YORK.

ALTERNATING-CURRENT CONTINUOUS-INDUCTION TRAIN-CONTROL SYSTEM.

Application filed February 25, 1921. Serial No. 447,675.

To all whom it may concern:

Be it known that I, ARCHIBALD G. SHAVER, a citizen of the United States, residing at Chicago, in the county of Cook and State of Illinois, have invented certain new and useful Improvements in Alternating-Current Continuous-Induction Train-Control Systems, of which the following is a specification, reference being had therein to the accompanying drawing.

This invention relates to improvements in a continuous induction train control system, one object of the invention being the provision of a train control system of this nature in which alternating current is employed and in which the train carried apparatus is such as to be affected the full length of the block or section of a block so that the failure of the current at any time, the reversal of flow of the current at any time, or the failure of any essential part of the system will produce a condition which will either stop the train or reduce the speed thereof.

A further object of this invention is the provision of a novel arrangement of inductoriums disposed adjacent the trackway and governed by roadside apparatus so that the train carried apparatus which also includes inductoriums associated with the track inductoriums and influenced by an alternating current generator, will be controlled by track conditions to actuate brake applying means upon the vehicle.

A still further object of this invention is the use of electrical energy on the locomotive for train control, so induced into roadside appurtenances as to be returned to the locomotive, of the proper characteristic to control the train without the necessity for operating energy along the roadside.

With the foregoing and other objects in view which will appear as the description of the invention proceeds, the invention resides in the combination and arrangement of parts and in the details of construction herein-after described and claimed, it being understood that changes in the precise embodiment of the invention herein disclosed can be made within the scope of what is claimed without departing from the spirit of the invention.

In the accompanying drawings:

Figure 1 is a diagrammatic view of the track equipment. 65

Figure 2 is a diagrammatic view of the vehicle carried equipment with the portion of the track equipment adjacent thereto.

Figure 3 is a detail view of one of the track inductoriums. 66

Figure 4 is a similar view of a modified form.

Referring to the drawings, and more particularly to Figure 1 thereof, there is shown provided for each block such as, for example, blocks A, B, C and D, a track battery 5 connected across the rails 6 and 10 and effective for normally energizing a home relay 8 also connected across the rails 6 and 10 by means of the conductors 7 and 9. 70

Each home relay 8 of a block controls or governs the energization of a distant relay associated with the next preceding block. Thus relay 8 of block C controls the distant relay 16 of block B and to this end the armature 13 of a home relay 8 is included in a circuit comprising a battery 11, conductor 12, contact 14, conductor 15, the distant relay 16 and return conductor 17. With this construction energization of a home relay 8 in attracting its armature 13 closes the distant relay circuit and energizes the distant relay 16 of the preceding block. 75

Each home relay 8 of a block also is associated with inductoriums of the next preceding block for affecting the same under certain track conditions. Disposed along the trackway either within the rails and parallel to each other preferably slightly below the tread of the rails or as shown in Figure 4 against the web of the rail adjacent the head thereof, are the track inductoriums 18 and 19 which may or may not have an iron core and which extend the full length of the blocks or track sections. 80

As shown in Figure 4, in lieu of a coil of wire, two or more strands of wire may be employed located adjacent the rail. In this latter instance the metal in the rail is used to amplify the effect of the current that is induced in the inductoriums 18 and 19. The track inductoriums 18 and 19 of a given block are intended for electrical connection and disconnection, depending upon track conditions, and to this 85 90 95 100

end there are provided the armature contact arms 20 and 21 under the influence of a distant relay 16 and the armature contact arms 22 and 23 under the influence of a home relay 8, both relays associated with the block in advance. Under clear track conditions as portrayed in Figure 1, when relays 8 and 16 of a block are both energized the inductorium 18 is connected in circuit with the inductorium 19, the circuit including the inductorium 18, a conductor 24, contact 25, the contact arms 20 and 22, conductor 26, the inductorium 19, conductor 27, the contact arms 23 and 21, contact 28 and conductor 29. When distant relay 16 is deenergized responsive to caution track conditions as will appear presently, the armatures 20 and 21 thereof will fall into engagement with lower contacts 30 and 31 associated therewith and connected to conductors 29 and 24 respectively, this engagement reversing with reference to relative instantaneous polarity, the connections between the inductoriums 18 and 19. Upon deenergization of a home relay 8 responsive to danger track conditions as will appear presently, the armature contact arms 22 and 23 open, breaking the connection between the inductoriums 18 and 19. It will therefore be seen with the provision of this construction that the track or home relay, such for example as the home relay 8 of block C, in controlling its armature 13 controls the distant relay 16 of block B, and in addition thereto also controls the armature contact arms 22 and 23 so that when the track or home relay 8 of block C is deenergized due to the presence of a train within said block or section C, the armature contacts 13, 22 and 23 will fall and open the circuits controlled thereby which in this instance are first, the circuit to the distant relay 16 of block B; and second, the circuit connecting the inductoriums 18 and 19 of said block B. The opening of the circuit connecting the said inductoriums 18 and 19 of block B is thus in response to danger track conditions and is intended, as will appear further hereinafter, for producing stop conditions on a train entering block B, and the opening of the circuit to the distant relay 16 of block B is intended, as will presently appear, for producing caution stop conditions on a train entering the block A. The latter operation is obtained when the deenergization of the distant relay 16 of block B effects the dropping of the armatures 20 and 21 controlled thereby, the dropping of these armatures into engagement with the lower contacts 30 and 31 respectively of the circuit including the inductoriums 18 and 19 of block A reversing the connections in this circuit, this producing, as will presently appear, caution indications in a train entering the said block A. Thus if a train were in block C the induc-

toriums 18 and 19 in block B would produce a stop, while the inductoriums in block A would produce a caution action on the vehicle.

Located upon the vehicle is an alternating current generator 32 which supplies current through the conductors 33 and 34 to the field 35 of the three position alternating current relay R, the return being made through conductors 36 and 37. As the generator is continuously operated the field 35 is continuously energized.

Under normal clear track conditions, and as shown in Figure 2, the circuits to the winding 35' of the relay R from the generator include the following: the generator 32, conductors 33 and 34, a transmitting inductorium 38 carried by the vehicle and conductors 36 and 37, inducing a current in the receiving track inductorium 19. Inductorium 19 when under clear track conditions is connected to inductorium 18, and the latter is energized when current is induced in the receiving inductorium 19, energization of inductorium 18 in turn influencing the coil or receiving inductorium 39 carried by the vehicle, a current being induced in the latter so that there is energy supplied to the relay winding 35' of the relay R, through the conductors 40 and 41. Under these conditions the armature 35' holds the contact arms 43 and 61 of the relay R in the full line positions as shown in Fig. 2.

The magnet valve 47 controlling the train braking system is normally energized through the following circuit, which includes the generator 32, the conductors 33, 34 and 42, the contact arm 43, contact 44, conductors 45 and 46, the magnet 47, and the conductors 48, 36 and 37. This magnet operates the combined reservoir and brake valve 49 which as shown in my Patent No. 1,411,526 of April 4, 1922, normally permits air to flow from the main reservoir to the engineer's brake valve through the pipes 50 and 51 and prevents the venting of the air brake system through the pipe 52 to the vent 53.

Should a distant relay 16 be de-energized, the armature contacts 20 and 21 being reversed so as to engage the back contacts 30 and 31 and therefore causing the reversal of flow of induced current to the relay winding 35', the contact arms 43 and 61 of the relay R will assume the extreme right dotted position, and the contact arm 43 will engage the contact 54 so that the speed circuit controller S is placed in series with the magnet 47 and so actuated as to prevent the movement of the train beyond a predetermined speed through a caution block. The speed control circuit includes the generator 32, the conductors 33, 34 and 42, the contact arm 43, the contact 54, the conduct-

tor 55, the contact 56, the switch 57 of the speed circuit controller S, the contact 58, the conductor 46, the magnet 47, and the conductors 48, 36 and 37.

5 Assuming that the train proceeds and enters a danger block, such as block B for example, home relay 8 of block C (assumed to be occupied by a train) will be deenergized and the armature contacts 22 and 23 10 of relay 8 in block C opened. Under these conditions no induced current will be permitted to flow from the inductorium 19 to the inductorium 18 of block B, and therefore no current will be supplied to affect 15 the relay winding 35' of the relay R. Under these conditions, the respective contact arms 43 and 61 will assume the central dotted position, opening the circuit to the magnet valve 47 by breaking the same at the 20 contact 48, while the contact arm 61 will engage the contact 60, the purpose of which will presently appear. As the speed of the train is reduced, the speed circuit controller will bridge contacts 56 and 58 and its switch 25 73 will bridge the contacts 72 and 74.

In order to proceed, after stopping the train, it is essential that the engine driver or motorman depress the release switch 65 which closes the following circuit including 30 the generator 32, the conductors 33, 34, 42, 59, contact 60, contact arm 61, the conductor 62, the electromagnet 63, the conductor 64, the hand release switch 65, the contact 66, and the conductors 67, 48, 36 and 37. Thus 35 the electromagnet 63 is energized attracting its contact arms 70 and 78 making stick contact 77 and closing contact 69. The release switch 65 need be closed only momentarily, and may now be opened. The following circuit is therefore closed to energize the magnet 47 and place the respective valves controlled 40 thereby in normal condition and governed by speed controller S. This circuit includes the generator 32, conductors 33, 34, 42, and 45 68, the contact 69, the contact arm 70, the conductor 71, the contact 72, the switch 73, the contact 74, conductors 75 and 46, magnet 47, and conductors 48, 36 and 37. The magnet 63 is also held energized after the opening 50 of the release key 65 through the following circuit and until the relay winding 35' is energized through the circuit including the inductorium. This circuit includes the generator 32, the conductors 33, 34, 42 and 55 59, the contact 60, the contact arm 61, the conductor 62, magnet 63, conductor 79, the stick armature 78, the contact 77, and conductors 76, 67, 48, 36 and 37.

The instant that the train is permitted to 60 proceed as when clear traffic conditions have been reestablished and the current is permitted to flow normally, the relay winding 35' of the relay R is energized so as to move the contact arms 43 and 61 to the full line position, thus opening the circuit to the mag-

net 63 so that its contact arms 70 and 78 fall opening their contacts 69 and 77 and the magnet 47 is maintained energized through its normal circuit with the speed circuit controller contacts eliminated from 70 the circuit. By this means the train is allowed to proceed without restriction.

It will be noted in Fig. 4 that the conductors 24' and 29' are enclosed in an insulating body 18' and are supported adjacent 75 the tread of the rail, and as above stated, the rail head is used to amplify the effect of the current that is induced into the wires 24' and 29'. In this instance, the coils 38 and 39 are supported so as to be slightly 80 above the rail head instead of within the rails, as shown in Fig. 2.

The two wires used to form the coils in the inductoriums 18 and 19 are so wound upon the wire core that they come out at 85 one end, the same being connected together through the relays so that the complete circuit is formed, closed within itself.

With this arrangement of apparatus, should the train after having received a caution indication then receive a clear unlimited proceed indication, the three position relay R will be energized in its normal position so that the valve magnet 47 will be energized 90 and the contacts of the speed circuit controller S eliminated from the circuit, thus permitting the train to proceed without any 95 speed restrictions.

While I have shown a particular circuit for applying this system of train control for 100 a practical operation, I do not wish to be limited to the same in detail as there are many arrangements of circuits that may be used to advantage and still be within the scope of my invention. I have also shown in 105 this application a double track operation but do not wish to be limited to the same as the scheme can be applied to a single track with very slight modifications.

A locomotive equipped as covered in this 110 invention may run forward or it may be turned around to run backward and yet it would operate equally well, because of the fact that where, for example, in the case of a locomotive running forward inductorium 115 38 would influence inductorium 19 and inductorium 19 would in turn influence inductorium 39, if the engine was turned around then inductorium 38 could just as well influence inductorium 18 and inductorium 19 120 could in turn influence inductorium 39.

It may also be desirable, instead of effecting a full stop, to permit the train to proceed at a low predetermined rate of movement after the train has been reduced to a 125 predetermined speed, which may for example, be about five miles an hour. This latter may be accomplished by placing the release key in the cab so that the engineer will have ready access thereto to press the same to 130

close the circuit after the low predetermined speed has been reached. Thus, when the key 65 is closed the relay 63 will be energized, thus energizing the electro-pneumatic valve 5 magnet 47 through the speed controller S, permitting the train to proceed.

It is intended that the winding on the inductoriums 18 and 19 will always be in the same direction, as for example, as shown in Fig. 3. Assume the ends 24 and 29 to be connected together, then the same wire always wound in the same direction would return to the opposite end of 18, the two ends being exposed at that end of core 18.

15 It will be noted with this arrangement that there is no necessity for trackside batteries or generators to influence the apparatus on the locomotive so that where this train control system is installed with the existing 20 block signal system it is not necessary to have trackside energy.

Although the inductoriums 18 and 19 are shown in parallel relation to each other and the rails, it is possible that the same may 25 be intermittently arranged on the outside of the rails as in mechanical and electrical ramp constructions, or extended the full length of the block as here shown, and by stating that the inductoriums are parallel 30 I mean that they may not necessarily be parallel but one might be at an angle to the other if found desirable.

What I claim as new is:

1. In an alternating current continuous 35 train controlling system, a trackway having two inductoriums paralleling the rails thereof, means for connecting the inductoriums in circuit operative for severing and for reversing the electrical connection therebetween, two inductoriums carried by the moving 40 vehicle, an alternating current generator connected to one of said vehicle inductoriums which is so disposed as to influence the other vehicle inductorium, 45 through the two track inductoriums, a relay controlled by one of said inductoriums and train controlling means under the influence of said relay.

2. In an alternating current continuous 50 train controlling system, a trackway with two inductoriums extending along the roadway, means for interrupting the flow of current from one to the other of said track inductoriums, means for altering the instantaneous polarity of the current in one of 55 said track inductoriums relative to that in the other, two inductoriums carried by the vehicle, a source of alternating electrical energy for energizing one of said vehicle 60 inductoriums which inductorium under certain conditions will influence the other vehicle inductorium through the medium of the two track inductoriums, a relay controlled by one of the vehicle inductoriums, 65 train controlling means under the influence

of said relay and a speed controller connected to influence the train controlling means and adapted to be connected to influence the same when the current flow is altered or interrupted.

3. In an alternating current continuous train controlling system, a trackway having two inductoriums paralleling the tracks thereof, means for severing the flow of induced current to one of the inductoriums, 70 means for changing the direction of flow of current to one of the inductoriums, two inductoriums carried by a moving vehicle, a continuously operating alternating current generator connected to one of said inductoriums and disposed to influence the other by the two inductoriums of the trackway, a three position relay controlled through one of the inductoriums of the vehicle, train controlling means under the influence of said relay, and electrically operated means including a manually controlled switch therefor and an auxiliary electrical control for closing the circuit between the generator and the train controlling means 75 after the train controlling means has been automatically actuated to control the train.

4. In a continuous inductive type of train control system, the combination with two inductoriums along the trackway, a home 80 block relay, a distant block relay, and circuit connections influenced by both of said relays for controlling the flow of induced current between the track inductoriums, of a vehicle carried mechanism including a 85 source of electrical energy, two inductoriums adapted to cooperate with the two inductoriums of the trackway, a circuit controlling means under the influence of said inductorium and vehicle controlling means 90 under the influence of said circuit controlling means.

5. In a continuous inductive type of train control system, the combination with two inductoriums along the trackway, a home 100 block relay, a distant block relay, and circuit connections influenced by both of said relays for controlling the flow of induced current between the track inductoriums, of a vehicle carried mechanism including a 105 source of electrical energy, two inductoriums adapted to cooperate with the two inductoriums of the trackway, a circuit controlling means under the influence of said inductoriums, vehicle controlling means under the influence of said circuit controlling means, a speed circuit controller, and a circuit connected with the vehicle controlling means and controlled by the speed circuit controller and by the said circuit controlling 110 means.

6. In a continuous inductive type of train control system, the combination with two inductoriums along the trackway, a home 115 block relay, a distant block relay, and cir- 120

cuit connections influenced by both of said relays for controlling the flow of induced current between the track inductoriums, of a vehicle carried mechanism including a 5 source of electrical energy, two inductoriums adapted to cooperate with the two inductoriums of the trackway, a circuit controlling means under the influence of said inductoriums, vehicle controlling means under the influence of said circuit controlling means, and manually controlled electrical means for connecting the source of electrical energy to the vehicle controlling means after the same has been automatically operated to bring the train to a halt.

7. In a continuous inductive type of train control system, the combination with two inductoriums along the trackway, a home block relay, a distant block relay, and circuit connections influenced by both of said relays for controlling the flow of induced current between the track inductoriums, of a vehicle carried mechanism including a 20 source of electrical energy, two inductoriums adapted to cooperate with the two inductoriums of the trackway, a circuit controlling means under the influence of said inductoriums, vehicle controlling means under the influence of said circuit controlling means, manually controlled electrical means for connecting the source of electrical energy to the vehicle controlling means after the same has been automatically operated to bring the train to a halt, and auxiliary 25 means for holding over the action of the said electrical means when the manual means thereof has been released.

8. In an alternating-current continuous train controlling system, a combination of 40 a trackway having two inductoriums running in a general direction parallel to the track rails, means responsive to danger track conditions for severing the electrical connection between said inductoriums, two inductoriums carried by the moving vehicle, an alternating current generator connected to one of said vehicle inductoriums which is so arranged that the other vehicle inductorium is influenced by current induced therein through the track inductoriums, a relay controlled by one of said inductoriums and train controlling means under the influence of said relay.

9. In a continuous induction type of train control system, a trackway having two inductoriums paralleling the tracks thereof and extending substantially the full length of a block or track section, means for affecting the flow of energy from one inductorium to another located along the trackway and controlled from a block in advance, a source of electrical energy, for influencing said inductoriums, carried upon a moving vehicle, a transmitting inductorium connected with said source and disposed to transmit

current to the roadside inductoriums, and train controlling means on the vehicle controlled through the influence of the transmitting and track inductoriums.

10. In an alternating current continuous 70 train control system, a trackway having two inductoriums paralleling the tracks thereof, means for severing the flow of induced current to one of said inductoriums, means for changing the direction of flow of current to one of said inductoriums, two inductoriums carried by a moving vehicle, a continuously operating alternating current generator connected to one of said vehicle carried inductoriums and disposed to 75 influence the other by the two inductoriums of the trackway, a two element relay controlled through one of the inductoriums of the vehicle, and train controlling means under the influence of said relay.

11. In an alternating current continuous 80 train controlling system, a trackway having two inductoriums paralleling the tracks thereof, means for severing the flow of induced current to one of said inductoriums, and means for changing the direction of flow of current to the same, two inductoriums carried by a moving vehicle, a continuously operating alternating current generator connected to one of said vehicle carried 85 inductoriums and disposed to influence the other by the two inductoriums of the trackway, a three position relay controlled through one of the inductoriums of the vehicle, train controlling means under the influence of said relay, and a speed circuit controller for influencing the train controlling means and adapted to be connected to influence the same when the direction of flow of current is reversed in one of the track inductoriums.

12. In an alternating current continuous 100 induction train control system, the combination with sets of parallel inductoriums paralleling the trackway, a home relay and a 110 distant relay for each set, the distant relay of one set being controlled by the home relay of another set, and circuit connections controlled by both of said relays for directing induced current to the track inductoriums, of a vehicle carried mechanism including an alternating current generator, two inductoriums adapted to cooperate with the inductoriums of the trackway, a three position 115 relay under the influence of said inductoriums, and vehicle controlling means under the influence of said relay.

13. In an alternating current continuous 120 induction train control system, the combination with sets of parallel inductoriums paralleling the trackway, a home relay and a distant relay for each set, the distant relay of one set being controlled by the home relay of another set, and circuit connections 125 controlled by both of said relays for direct- 130

- ing induced current to the track inductoriums, of a vehicle carried mechanism including an alternating current generator, two inductoriums adapted to cooperate with the inductoriums of the trackway, a three position relay under the influence of said inductoriums, vehicle controlling means under the influence of said relay, a speed circuit controller, and a circuit connected with the vehicle controlling means and controlled combinedly by the speed circuit controller and the relay due to the reversal of flow of induced current to a winding thereof.
14. In an alternating current continuous induction train control system, the combination with sets of parallel inductoriums paralleling the trackway, a home relay and a distant relay for each set, the distant relay of one set being controlled by the home relay of another set, and circuit connections controlled by both of said relays for directing induced current to the track inductoriums, of a vehicle carried mechanism including an alternating current generator, two inductoriums adapted to cooperate with the inductoriums of the trackway, a three position relay under the influence of said inductoriums, vehicle controlling means under the influence of said relay, and manually controlled electrical means for connecting the generator to the train controlling means after the same has been automatically operated to bring the train to a halt.
15. In an alternating current continuous induction train control system, the combination with sets of parallel inductoriums paralleling the trackway, a home relay and a distant relay for each set, the distant relay of one set being controlled by the home relay of another set, and circuit connections controlled by both of said relays for directing induced current to the track inductoriums, of a vehicle carried mechanism including an alternating current generator, two inductoriums adapted to cooperate with the inductoriums of the trackway, a three position relay under the influence of said inductoriums, vehicle controlling means under the influence of said relay, manually controlled electrical means for connecting the generator to the train controlling means after the same has been automatically operated to bring the train to a halt, and auxiliary means for holding over the action of the latter means when the manual means thereof has been released.
16. In an alternating current continuous induction train control system, the combination with two parallel inductoriums paralleling the trackway, a home relay and a distant relay, the latter being controlled by the former and circuit connections controlled by both of said relays for governing induced current to the track inductoriums, of a vehicle carried mechanism including an alter-
- nating current generator, two inductoriums adapted to cooperate with the two inductoriums of the trackway, a three-position relay under the influence of said inductoriums and vehicle controlling means under the influence of said relay.
17. In an alternating current continuous induction train control system, the combination with sets of parallel inductoriums paralleling the trackway, a home relay and a distant relay for each set, the distant relay of one set being controlled by the home relay of another set and circuit connections controlled by both of said relays for directing induced current to the track inductoriums, of a vehicle carried mechanism including an alternating current generator, two inductoriums adapted to cooperate with the two inductoriums of the trackway and vehicle controlling means under the influence of said inductoriums.
18. In a continuous inductive train control system, the combination with the track rails sub-divided into a plurality of sections or blocks, of roadside mechanism comprising a plurality of parallel inductoriums for each section or block disposed substantially the full length of the block, roadside means operable in response to track conditions for connecting the inductoriums in circuit under "clear" track condition and operative to disconnect the same under a "danger" track condition.
19. In a continuous inductive train control system, the combination with the track rails sub-divided into a plurality of sections or blocks, of roadside mechanism comprising a plurality of parallel inductoriums for each section or block disposed substantially the full length of the same, roadside means operable in response to track conditions for changing connections between the inductoriums for reversing the instantaneous direction of flow of current in one inductorium relative to the other and for discontinuing the flow of current in one of said inductoriums under predetermined conditions.
20. In a continuous inductive train control system, the combination with the track rails sub-divided into a plurality of sections or blocks, of roadside mechanism comprising a plurality of parallel inductoriums for each section or block disposed substantially the full length of the same, roadside means operable in response to track conditions for reversing circuit connections to one of said inductoriums, and additional roadside means also operable in response to track conditions for breaking circuit connections to one of said inductoriums.
21. In a continuous inductive train control system, the combination with the track rails sub-divided into a plurality of sections or blocks, of roadside mechanism comprising

- a plurality of roadside inductoriums for each section or block disposed substantially the full length of the same, and means for connecting the same operative to reverse circuit connections therebetween. 5
22. In a continuous inductive train control system, the combination with the track rails sub-divided into a plurality of sections or blocks, of roadside mechanism comprising 10 a plurality of roadside inductoriums for each section or block disposed substantially the full length of the same, and means for connecting the same operative to reverse circuit connections therebetween and for breaking circuit connections therebetween. 15
23. In a continuous inductive train control system, the combination with the track rails sub-divided into a plurality of sections or blocks, of roadside mechanism comprising 20 a plurality of roadside inductoriums for each section or block disposed substantially the full length of the same, and means for
- connecting the same operative to reverse circuit connections therebetween and for breaking circuit connections therebetween, the 25 said means comprising a pole changer and a make and break device. 24. In an induction train control system, the combination with two parallel inductoriums paralleling the trackway and of 30 substantially equal length, a home relay and a distant relay, the latter being controlled by the former, and circuit connections to said inductoriums controlled by said relays. 25. In an induction train control system, the combination with sets of parallel inductoriums paralleling the trackway, a home relay and a distant relay for each set, the 35 distant relay of one set being controlled by the home relay of another set, and circuit connections to a set of inductoriums controlled by both said relays of one set. 40

In testimony whereof I affix my signature.

ARCHIBALD G. SHAVER.
